US0D1055000S

(12) **United States Design Patent** (10) **Patent No.:** **US D1,055,000 S**
(45) **Date of Patent:** **** Dec. 24, 2024**

(54) **WIRE CONNECTOR**

(71) Applicant: **Jeffrey P. Baldwin**, Anthem, AZ (US)

(72) Inventor: **Jeffrey P. Baldwin**, Anthem, AZ (US)

(73) Assignee: **Titan3 Technology LLC**, Tempe, AZ (US)

(**) Term: **15 Years**

(21) Appl. No.: **29/838,256**

(22) Filed: **May 11, 2022**

(51) LOC (14) Cl. **13-03**

(52) U.S. Cl.

USPC **D13/150**

(57) **CLAIM**

The ornamental design for a wire connector as shown and described.

DESCRIPTION

FIG. 1 is a front view of a wire connector showing my new design;

FIG. 2 is a right-side view thereof;

FIG. 3 is a left-side view thereof;

FIG. 4 is a top view thereof;

FIG. 5 is a bottom view thereof;

FIG. 6 is a rear view thereof;

FIG. 7 is a top, right perspective view thereof; and,

FIG. 8 is a top, left perspective view thereof.

The broken lines in the figures represent portions of the wire connector that form no part of the claimed design.

1 Claim, 8 Drawing Sheets
